(57) **CLAIM**

The ornamental design for a SIM card connector, as shown and described.

DESCRIPTION

FIG. 1 is a perspective view of a SIM card connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of the SIM card connector showing our new design.

The broken line of the internal elements of the connector in FIG. 7 is included to show unclaimed subject matter only and forms no part of the claimed design.

1 Claim, 8 Drawing Sheets

FIG. 1
